[57] **ABSTRACT**

There are provided novel polyene hydrocarbons containing two conjugated double bonds and having the following general formula

wherein R is hydrogen or alkyl and R₁, R₂, R₃, R₄, R', R'' and R''' are hydrogen, alkyl or aryl.

4 Claims, No Drawings

POLYENE HYDROCARBONS CONTAINING TWO CONJUGATED DOUBLE BONDS AND PROCESS FOR OBTAINING SAME

The present invention relates to new polyene hydrocarbons containing two conjugated double bonds and to the process for obtaining same. 5

More particularly the present invention relates to triene hydrocarbons having the following general formula:

in which R is hydrogen or an alkyl radical; R₁, R₂, R₃, R₄, R', R'', and R''' may be hydrogen, alkyl or aryl radicals.

These hydrocarbons are obtained by reacting a substituted or unsubstituted norbornene carbonyl derivative with a 20 Grignard alkenyl derivative, for example according to the following scheme:

wherein R₁, R₂, R₃, R₄, R, R', R'', and R''' have the aforesaid meanings and X is a halogen as Br, Cl or I.

It is also possible to react a substituted or unsubstituted Grignard compound of the norbornadiene halogen derivative with a ketone and then to dehydrate the corresponding alcohol, according to the scheme

wherein R₁, R₂, R₃, R₄, R, R', R'', R''' and X have the known meanings. Another unrestricted example of the invention is the Diels-Alder reaction between the substituted or unsubstituted cyclopentadiene and an acetylene derivative containing at least a double bond adjacent to the triple bond:

All the above reactions are carried out at a temperature 10 ranging from 0° to 100° C, and preferably in the presence of a solvent which may be selected from ethers as tetrahydrofuran, dioxane, ethyl ether, butyl ether, and the like, from aromatic hydrocarbons as benzene, toluene, xylenes or mixtures of these solvents.

15 Typical unrestricted examples of triene derivatives according to the present invention are the following ones:

2-propenyl-norbor-2,5-diene

2-(butenyl-2') 3-methyl-norbor-2,5-diene

isopropylidene-norbornadienyl-methane

The invention is now illustrated by the following unrestricted examples.

EXAMPLE I

In a three neck flask provided with a reflux condenser and a mechanical stirrer, a tetrahydrofuran solution of decahydronorcanfor was added to a tetrahydrofuran 2M solution of the Gringard derivative of 1-bromo-1-propene.

45 After a prudent mixing of the reactants, the reaction mass was allowed to reflow for 2 hours: then the magnesium salts were dissolved by an excess of a watery CH₃COOH (1:1 by volume), the organic phase was washed up to neutrality, dried on Na₂SO₄ and the tetrahydrofuran was removed by distillation.

50 The remaining alcohol was already dehydrated during the distillation at reduced pressure (0.5 mmHg); in such a way the product I was obtained, having a b.p. = 45° C/10 mmHg and a MW = 132 (mass spectrometry).

EXAMPLE II

The condensation product of cyclopentadiene with alpha-bromo-acrolein was dehydrohalogenated into formylnorbornadiene. This compound was prudently treated with an excess of the Gringard reactant of 2-bromo-propane. The alcohol, obtained from the reaction mass according to the preceding example, was dehydrated on α Al₂O₃ at 230° C and a product was obtained having a boiling point of 55° C at 10 mmHg, a molecular weight equal to 146 (mass spectrometry), it being in agreement with the structure III.

EXAMPLE III

70 By employing suitable catalyst [according to Dt. Botz, C. Bucur, J. Primus, L. Stanescu-Rev. Chimi (Budapest) 12, 503 (1961) C.A. 56 5848 g (1962) and to F.P. 1,364,969] cyclopentadiene was allowed to react with 3-methyl-2-esen-4-ino at 144° C: the obtained produce was rectified and the compound II was obtained showing a well

agreement with the proposed structure at the physical-chemical investigation.

What we claim is:

1. Polyene hydrocarbons containing two conjugated double bonds and having the following general formula:

in which R is hydrogen or an alkyl radical; R₁, R₂, R₃, R₄, R', R'' and R''' are hydrogen, alkyl or aryl radicals.

2. A process for preparing polyene hydrocarbons as claimed in claim 1 characterized in that a carbonyl derivative as:

is allowed to react with an alkenyl Grignard derivative as:

10

wherein R₁, R₂, R₃, R, R', R'' and R''' have the aforesaid meanings; and X is a halogen as Cl, Br or I.

5 3. A process for preparing polyene hydrocarbons as claimed in claim 1 characterized in that said hydrocarbons are obtained by reacting a Grignard derivative as:

15 with a ketone as

20

wherein R, R₁, R₂, R₃, R₄, R', R'', R''', and X have the aforesaid meanings.

25 4. A process for preparing polyene hydrocarbons as claimed in claim 1 characterized in that cyclopentadiene is allowed to react with an acetylene derivative containing at least a double bond conjugated with the triple bond.

UNITED STATES PATENT OFFICE
CERTIFICATE OF CORRECTIONPatent No. 3,676,511 Dated July 11, 1972Inventor(s) Sergio Arrighetti, et al

It is certified that error appears in the above-identified patent
and that said Letters Patent are hereby corrected as shown below:

Column 1, line 45, correct the second formula as follows:

Column 2, line 74, change "produce" to --product--.

Column 4, line 4, after "R₃" correct "R", first occurrence,
to -- R₄ --.

Signed and sealed this 19th day of February 1974.
